CLAIM

The ornamental design for a controller for broadcast lenses, as shown and described.

DESCRIPTION

FIG. 1 is a front view of a controller for broadcast lenses;
 FIG. 2 is a back view thereof;
 FIG. 3 is a top view thereof;
 FIG. 4 is a bottom view thereof;
 FIG. 5 is a left side view thereof;
 FIG. 6 is a right side view thereof; and,
 FIG. 7 is a perspective view thereof.

The broken lines show portions of the controller for broadcast lenses that form no part of the claimed design.
